UNITED STATES PATENT OFFICE.

THOMAS B. ANDERSON, OF CHESTER, WEST VIRGINIA.

DESIGN FOR A DISH OR SIMILAR ARTICLE.

50,052.

Specification for Design.

Patented Dec. 19, 1916.

Application filed July 25, 1916. Serial No. 111,251. Term of patent 3½ years.

To all whom it may concern:

Be it known that I, THOMAS BAIRD ANDERSON, a citizen of the United States, residing at Chester, in the county of Hancock and State of West Virginia, have invented a new, original, and ornamental Design for a Dish or Similar Article, of which the following is a specification, reference being had to the accompanying drawing, forming part thereof.

Figure 1 is a top plan view of a dish showing my new design. Fig. 2 is a side view of the dish shown in Fig. 1. Fig. 3 is a detail fragmentary sectional view through Fig. 2 on line 3—3, showing the ornamental arrangement of the raised portion.

I claim:

The ornamental design for a dish or similar article, as shown and described.

THOMAS B. ANDERSON.
